HYDRAULIC PRESS

Richard W. Dinzl, Westfield, N. J., assignor to The Watson-Stillman Co., Roselle, N. J., a corporation of New Jersey

Application August 4, 1939, Serial No. 288,326

4 Claims. (Cl. 113—45)

This invention relates more particularly to improvements in forming presses of a type used for metal stamping, shearing, and the like. Often, such a press is required to operate upon a work-piece so shaped as to dispose the load or stress of the work resistance off-center with respect to the press heads or platens operating upon the work. In that case the powerful off-center stress sometimes cant a press head slightly, with consequent damage to the dies, the work, or both. Methods of correcting this defect have been proposed but heretofore they have involved complications in the press structure which are objectionable in operation and add materially to the cost of the press.

An important object of the present invention is to provide simple, inexpensive and entirely satisfactory means for preventing the said tilting of a press head under the stress of off-center work resistance.

Other objects of the invention will appear hereinafter.

In the drawings, Fig. 1 is a vertical sectional view of a press embodying the invention, the section being on the line 1—1 of Fig. 3;

Fig. 2 is an enlarged detail vertical section on the line 2—2 of Fig. 4;

Fig. 3 is a side view of the press;

Fig. 4 is an enlarged horizontal section on the line 4—4 of Fig. 3; and

Fig. 5 is a view similar to Fig. 2, showing a modified form of the press head guiding means.

The invention is shown as embodied in a press having a fixed lower press head and a cooperating upper press head reciprocable vertically by hydraulic pressure. The press includes a rigid frame whose structure comprises a lower transverse frame member or base 1, columns 2 borne by the base, at opposite sides of the press heads, a transverse frame member 3 supported by the columns in a position above the press heads, a transverse frame member 4 spaced above the member 3, and four strain rods 5 to anchor together all of said parts of the frame. Base 1 comprises a flat casting bearing upon its upper face a flat bolster plate 6 which forms in effect the fixed lower press head or platen. Each column 2 is also a casting formed to define a pair of spaced tubular portions each of which forms a housing for a strain rod. Frame member 3 rests upon the upper ends of the columns. A pair of keys 7 are inserted in key-ways in the abutting surfaces of the column and the member 3 and hold the latter against endwise displacement on the columns. Another pair of keys 8 at right

angles to the first pair are also inserted in key-ways in said abutting surfaces and hold the member 3 against sidewise displacement on the columns. At their lower ends the columns are similarly keyed to the base. The strain rods extend through holes in the base, the frame member 3 and the frame member 4 and have nuts 9 screwed upon their upper and lower ends to anchor together all of the frame parts. Between the frame members 3 and 4, rigid spacing sleeves 10 encircle the strain rods and support the member 4 properly spaced above the member 3.

An upper press head or platen 11 comprising a rigid casting is mounted for vertical reciprocation between the columns 2. Between each column and the adjacent side of said press head there are guide means for the head. Each column is formed with a pair of square corners adjacent the press head and bears, at said corners, rigid guide strips 12. Each of the latter is beveled to provide it with a vertical guide face 13 which faces obliquely inwardly toward the press head. A rigid flange 14 formed on the guide strip bears against the outer side of the corner of the column and is secured to the column by screws 15. The press head 11 has four vertical channels 16 opposed to the guide faces 13 and each with a bottom surface 17 parallel to the adjacent guide face. Between the opposed surfaces 13 and 17 there is a vertical guide member 18 having an inclined face 19 opposed to the guide face 13. Between said guide member and the face 18 there is fitted a companion wedge-shaped guide member 20 having a vertical guide face 21 slidably fitting against the face 18 and an inclined face 22 fitting against the inclined face of guide member 18. The latter member has a rounded protuberance 23 rotatably fitting in a rounded cavity 24 in the surface 17 to enable the guide members to be accurately trued to the surface 18. Between said companion guiding members there is a screw connection 25 for vertically adjusting the member 20 to accurately fit the guide face 18.

Above the press head 11 and centered thereon there is a hydraulic pressure cylinder 26. This cylinder forms part of the hydraulic means for moving the head 11 downward on its working stroke and also serves as part of additional guide means to cooperate with the press head guiding means previously described and hold the press head against tilting under working stress. The cylinder is a hollow casting vertically arranged and formed at its lower end with a base flange 27 which bears against the upper side of the press 55

head 11 and is bolted thereto, as at 28, to make the cylinder and press head a rigid, reciprocable unit. The cylinder casting is formed with a partition 29 at an intermediate point, and the portion 5 of the casting above said partition forms the actual hydraulic press cylinder. It is open at its upper end and into it protrudes a fluid pressure reaction plug 30 with packing 31 therearound. This plug depends from the top frame member 10 4 and is supported thereby in a fixed position. Its upper end portion is reduced and extends upward through a bore 31a in the frame member 4. The shoulder 32 at the base of the reduced portion abuts the under surface of the member 4. At its 15 upper end the plug is screw-threaded and has a nut 33 screwed thereon and bearing against an abutment surface on the member 4 around the upper end of the bore 31. The plug has an axial bore 34 for admitting fluid pressure to the cylinder to act upon the partition 29 and force the cylinder and press head 11 downward on a working stroke. The bore 31a containing the reduced portion of the plug is preferably slightly larger than said portion to enable lateral adjustment 20 of the plug to center it within the cylinder.

The cylinder casting 26 is much longer than the stroke of the press head 11 and it extends upward through a vertical bore 35 in the frame member 3. This bore is materially larger than 30 the cylinder casting and has fitted therein a rigid annular guide 36 for the cylinder. The bore of this guide and the peripheral surface of the cylinder are finished smooth and they have a snug sliding fit. At its lower end the guide has 35 a flange 37 bolted to the under side of the frame member 4, as at 38.

The cylinder guide 36, the cylinder casting 26, the press head guide members 20 and the fixed guide members 12 borne by the frame columns 40 are so formed and arranged that the most remote guiding points of the guide 36 and the guides 20, that is, the highest point of engagement of the guide 36 with the cylinder casting and the lowest point of engagement of the guides 45 20 with the fixed guide surfaces 13, are spaced along the vertical line of reciprocation of press head 11 a distance at least equal to the major dimension of the working face area of said press head. By working face area is meant the maximum area practically available at the under face 50 of the press for bearing a die for cooperation with a die on the companion lower press head 6. The guides 36 and 20 are of material length along the line of reciprocation, and the length of the 55 guiding surface of the cylinder and that of the fixed guide surfaces 13 is such that the entire length of guide 36 and of guides 20 will be in guiding engagement with said surfaces respectively in all positions of the press head 11 along 60 its stroke.

The means shown and described for guiding the reciprocable press head and cylinder unit will positively resist tilting of the press head under the stress of off-center work resistance due to 65 non-symmetrical arrangement of the work with reference to the axial line of the press cylinder or the center of the press head. The wide spacing of the cylinder guide 36 from the guides 20 along the line of reciprocation provides the guide 36 70 with a large moment of resistance to positively resist canting of the press head 11 and prevent damage to the dies and the work.

The press head 11 and the bolster plate 6 may be provided with the usual means for supporting 75 cooperating dies thereon. Said means and the

dies are here omitted from the drawings in order to simplify the illustration. For the same reason, means for supplying hydraulic pressure to the bore 34 delivering to the press cylinder, and means for controlling the pressure in the cylinder, are omitted from the drawings.

For retracting or elevating the press head 11 the press is provided with the usual hydraulic pull-back cylinders 39 and pistons 40. Said cylinders are supported by the press frame member 3, and the pistons are operatively connected by rods 41 to the press head 11. By admission of hydraulic pressure to the cylinders, at the under side of the pistons, the press head is raised. Any suitable means, not shown, may be employed to supply and control hydraulic pressure in the pull-back cylinders.

Fig. 5 shows another form of press head guiding means, simpler than that shown in Figs. 2 20 and 4, for cooperation with the fixed guides 12. A single guide strip 20a is fitted within each of the corner channels 16 of the press head 11 and is formed to fill the space between the bottom face of the channel and the fixed guide face 13.

What I claim is:

1. In a press, the combination of a rigid lower press head, a transverse upper frame member and vertical side frame members rigid with the transverse member, a vertically arranged press head guiding means below the upper transverse member and located at the outer margin of the reciprocable head, a vertical press cylinder rigid with the reciprocable press head and centered thereon and extending upwardly from the upper surface thereof and through the said upper frame member and adapted to receive fluid pressure, said cylinder being smaller in diameter than the transverse dimension of the said reciprocable head, rigid annular means borne by said upper frame member and extending around said cylinder and having a long bearing on the exterior thereof, the cylinder extending through and above said guide means to guide the cylinder in its reciprocation with the upper press head; a fluid pressure reaction plug borne by the frame in a fixed central position above the said upper frame member and extending down into the upper end of the cylinder and along which the cylinder is slidable; annular fluid pressure retaining and rigid annular cylinder-guiding means carried by the cylinder at the upper end thereof and between the cylinder and said plug, said fluid-pressure retaining and cylinder guiding means being smaller in diameter than the said annular guiding means engaging the exterior of the cylinder, whereby the reciprocable press head and the cylinder will be guided by three vertically spaced guiding means located different distances outward from the axis of the cylinder, the guiding means for the press head being the lowermost and at the greatest distance outward from the cylinder axis and the uppermost of said guiding means being the shortest distance outward from said axis.

2. In a press, the combination of a rigid press frame comprising a transverse lower frame member bearing a lower head, a transverse upper frame member, and vertical side frame members rigid with the transverse members, a vertically reciprocable rectangular upper press head, vertically arranged press head guiding means below the upper transverse member and between the vertical frame members and located at the four corners of the reciprocable head the engaged faces of said guide means in horizontal section 75

being in planes approximately forty-five degrees to a vertical plane extending centrally and longitudinally of the press, a vertical press cylinder rigid with the reciprocable press head and centered thereon and extending upwardly from the upper surface thereof and through the said upper frame member and adapted to receive fluid pressure for moving both the cylinder and the upper head downward on a working stroke, said 10 cylinder being smaller in diameter than the transverse dimension of the said reciprocable head, rigid annular guide means borne by said upper frame member and extending around said cylinder and having a long bearing on the exterior thereof, the cylinder extending through and above said guide means to guide the cylinder in its reciprocation with the upper press head; a fluid pressure reaction plug borne by the frame in a fixed central position above the said upper frame 15 member and extending down into the upper end of the cylinder and along which the cylinder is slideable; annular fluid pressure retaining and rigid annular cylinder guiding means carried by the cylinder at the upper end thereof and between the cylinder and said plug, said fluid pressure retaining means being smaller in diameter than the said annular guiding means engaging the exterior of the cylinder, whereby the reciprocable press head and the cylinder will be guided by three vertically spaced guiding means located different distances outward from the axis of the cylinder, the lowermost of said guiding means being the greatest distance outward from the cylinder axis and the uppermost of said guiding 20 means being the shortest distance outward from said axis.

3. In a press, the combination of a rigid press frame comprising a transverse lower frame member bearing a lower head, a transverse upper frame member, and vertical side frame members rigid with the transverse members, a vertically reciprocable rectangular upper press head, vertically arranged press head guiding means below the upper transverse member and between the vertical frame members and located at the four corners of the reciprocable head the engaged faces of said guide means in horizontal section being in planes approximately forty-five degrees to a vertical plane extending centrally and longitudinally of the press, adjustable wedge means between the vertical edges of the press head and the said vertical guiding means, a vertical press cylinder rigid with the reciprocable press head and centered thereon and extending upwardly from the upper surface thereof and through the said upper frame member and adapted to receive fluid pressure for moving both the cylinder and the upper head downward on a working stroke, said cylinder being smaller in diameter than the transverse dimension of the said reciprocable head, an annular means borne by said upper frame member and extending around said cylinder and having a long bearing on the exterior

thereof, the cylinder extending through and above said guide means to guide the cylinder in its reciprocation with the upper press head; a fluid pressure reaction plug borne by the frame in a fixed central position above the said upper frame 5 member and extending down into the upper end of the cylinder and along which the cylinder is slideable; annular fluid pressure retaining and rigid annular cylinder guiding means carried by the cylinder at the upper end thereof and between the cylinder and said plug, said fluid pressure retaining means being smaller in diameter than the said annular guiding means engaging the exterior of the cylinder, whereby the reciprocable press head and the cylinder will be guided by three vertically spaced guiding means located different distances outward from the axis of the cylinder, the lowermost of said guiding means being the greatest distance outward from the cylinder axis and the uppermost of said guiding 10 means being the shortest distance outward from said axis.

4. In a press, the combination of a rigid lower press head, a transverse upper frame member and vertical side frame members rigid with the transverse member, a vertically arranged press head guiding means below the upper transverse member and located at the outer margin of the reciprocable head, adjustable wedge means between the vertical edges of the press head and the said 25 vertical guiding means, a vertical press cylinder rigid with the reciprocable press head and centered thereon and extending downward from the upper surface thereof and through the said upper frame member and adapted to receive fluid pressure, said cylinder being smaller in diameter than the transverse dimension of the said reciprocable head, rigid annular means borne by said upper frame member and extending around said cylinder and having a long bearing on the exterior 30 thereof, the cylinder extending through and above said guide means to guide the cylinder in its reciprocation with the upper press head; a fluid pressure reaction plug borne by the frame in a fixed central position above the said upper frame member and extending down into the upper end of the cylinder and along which the cylinder is slideable; annular fluid pressure retaining and rigid annular cylinder-guiding means carried by the cylinder at the upper end thereof and between the cylinder and said plug, said fluid pressure retaining and cylinder guiding means being smaller in diameter than the said annular guiding means engaging the exterior of the cylinder, whereby the reciprocable press head and the cylinder will be guided by three vertically spaced guiding means located different distances outward from the axis of the cylinder, the guiding means for the press head being the lowermost and at the greatest distance outward from the cylinder axis and the uppermost of said guiding 35 means being the shortest distance outward from said axis.

RICHARD W. DINZL.
